UNITED STATES PATENT OFFICE.

PAUL HANNAGAN, OF LAWRENCE, MASSACHUSETTS; CATHERINE T. HANNAGAN
ADMINISTRATRIX OF SAID PAUL HANNAGAN, DECEASED.

TRAFFIC-POST.

1,341,318.

Specification of Letters Patent.

Patented May 25, 1920.

Application filed December 22, 1916. Serial No. 138,447.

To all whom it may concern:

Be it known that I, PAUL HANNAGAN, a citizen of the United States, residing at Lawrence, in the county of Essex, State of Massachusetts, have invented a certain new and useful Improvement in Traffic-Posts, of which the following is a specification, reference being had therein to the accompanying drawings.

10 The invention comprises various improvements in traffic-posts or semaphores employed for directing and controlling vehicular and other traffic on streets, drives, ways, etc. It provides an improved post 15 that is so constructed that when run down by a vehicle it will yield without breakage so as to permit of the passage of the vehicle over it, and after the vehicle has passed on will erect itself into its working 20 position again. It also provides a traffic-post or semaphore which when not required to occupy its working position, may be lifted up, turned upside down, and lowered beneath the surrounding surface out of the 25 way, the construction preferably being such that the opening into which the post or semaphore is thus lowered is closed by a member which at such time serves as a cover for the said opening, in addition to 30 serving as a base for the post when the latter occupies its working position.

Embodiments of the features of the invention are shown in the drawings, in which latter,—

35 Figure 1 shows in elevation one of such embodiments, and represents in section the roadway in which it is planted, the post being in working position.

Fig. 2 is a view showing the said embodiment with one side of the post-member removed, and the lower end of the post-member as well as the base-member, in vertical section.

40 Fig. 2^a is a plan of the foot of the post shown in Figs. 1 and 2.

Fig. 2^b is a view in section on line 2^b, 2^b, of Fig. 2^a.

Fig. 3 is a view similar to Fig. 1, showing the post turned upside down and housed 50 below the surface of the roadway.

Fig. 4 is a side elevation of the base-member.

Fig. 5 is a plan view thereof.

Fig. 6 is a bottom view thereof.

Fig. 7 is a view in vertical section on 55 lines 7, 7, of Figs. 4, 5 and 6.

Fig. 8 is a view in horizontal section on line 8, 8, of Fig. 4.

Fig. 9 is a view showing the construction, etc., when the working position of a traffic- 60 post is over a subway, pipes, etc., approaching closely to the surface of the roadway.

Fig. 10 is a sectional representation of the construction of a portable traffic-post 65 adapted to be temporarily placed in any required position and to be shifted at will.

Figs. 11 and 12 show a construction employing a weight instead of a spring to cause the post to right or erect itself.

Fig. 13 shows a modified construction 70 provided with lamps.

Fig. 14 is a sectional view of the base-member of Fig. 13, with its lamp.

Having reference to the drawings,—

Each of the different forms of embodiment of my invention represented herein 75 comprises a post-member, a base-member combined with one end of the post-member, and a socket-member which receives the said base-member.

In Figs. 1 to 8, the post-member 1 is mounted by its lower end or foot upon the base-member 2, and the said base-member occupies and fits a seat within the socket-member 3. In this embodiment of the in- 85

vention, as in certain others, the socket-member 3 is in the form of a shell or pipe and is sunk in a vertical or upright position in the roadway 4, with its upper end flush with the surface of the roadway. The 90

bottom end of the socket-member preferably is open to provide for drainage. The seat in the upper end of the socket-member is furnished with an internal shoulder 5 on which the base-member 2 rests, and by 95

which the base-member and post are supported vertically. The wall of the seat above the shoulder affords lateral support to the base-member, the vertical extent of the contact between the exterior bearing- 100

surface of the base-member and the said wall being sufficient to prevent the base-member from tipping. The post is combined with the base-member in a manner and by means providing for holding the 105

post normally upright upon the base-member, but providing in addition for tipping or tilting of the post relative to the base-

member while the base-member remains in normal position in its seat in the top of the socket-member. In this embodiment the base-member is furnished with a central 5 upwardly tapering or rounded boss 6, around the base of which is formed a horizontal shoulder 7, around which in turn a groove 8 is formed in the top of the base-member, the base-member being provided 10 with a raised rim 9 outside the said groove. The lower end of the post extends down around the said boss, and its foot 10 rests upon the shoulder 7, whereby the post is supported vertically upon the base-member. 15 The outer margin of the foot projects over the groove 8 and fits within the raised rim 9, which rim serves to restrain the foot from lateral movement upon the base-member. The foot is held by yielding force in firm 20 contact with the shoulder 7, and the post thereby maintained in upright or working position. In this instance this is accomplished by means of a contracting spiral spring 11, the upper end of which is engaged 25 with an elevated interior bridge-piece 12 within the post, while the lower end of the spring is engaged with the base-member by means of a screw-eye or eye-bolt 13 that is combined with the center of 30 the boss of said base-member. I find the best results in causing the post to recover its upright position are secured by locating the point of engagement of the lower end of the spring with the base-piece at a point 35 somewhat elevated relative to the level at which the foot of the post rests upon shoulder 7.

To save material and reduce weight, the base-member is made hollow, with openings 40 6^a in the upper part of its shell to give access to the nut on the lower end of the screw-eye or eye bolt 13; also with vertical drainage holes 8^a, 8^b, leading from groove 8 to the interior of the shell; and also with 45 lateral drainage openings 8^b, 8^b, in the lower part of the shell.

The body of the post may be of any approved shape in cross-section, usually square as in the drawings. Its construction may 50 vary in practice, but usually it consists of a hollow shell, which may be of sheet-metal. The foot 10 may be an integral portion of the said body, but usually is a separate piece formed with an upwardly-projecting rim or series of lugs to which the lower end of the post-body is fastened.

In use, should a vehicle run against the post, the spring will yield and allow the post to be pressed over. As the post gives 55 way under the pressure, the foot will rock at one side of the center upon the inner edge of the groove 8, the margin of the foot adjacent the point on which the foot rocks or pivots upon the said edge dipping into 60 the groove until said margin bears against

the inner wall of the groove. The said inner wall will limit the extent of inward slipping of the foot as the swinging movement is continued, and the post will simply swing, as upon a pivot, upon the portion of the 70 foot which bottoms in the groove and bears against the inner wall of the groove, stretching the spring in so doing and thereby increasing the tension of the spring. As soon as the post is released from the pressure 75 which carried it away from its normal working position, the spring will operate to swing the post reversely into an erect position again. The tapered or rounded shape of the boss 6 upon the base-member will center the foot of the post, and prevent any lateral displacement of the foot relative to the base-member as the post rises to the normal working position.

When it is desired to house the post as in 80 Fig. 3, it is lifted bodily upward so as to withdraw the base-member from the seat therefor in the socket-member. Then the post is turned upside down, and is passed downward within the socket-member until 85 the raised rim 9 of the base-member comes to rest upon the internal shoulder 5 of the socket-member.

To permit the post to be thus housed, the shell or pipe of the socket-member is made 90 long enough interiorly to accommodate the length of the post. The base-member fills the upper portion of the socket-member in this inverted position thereof, and its bottom surface, now presented on top, is flush 100 with the adjoining surface of the roadway. A ring 14 connected loosely with the said bottom-surface serves as a convenient hand-hold in lowering the inverted post and base-member into place within the socket-member, and in withdrawing them preliminary 105 to reinstating the post in its normal working position.

In some locations where the employment of a traffic-post is desirable, it is not feasible to 110 plant therein a socket-member of a length or depth sufficient to provide for the housing of the inverted post and base-member. The roof of a subway, or of a sewer or some other structure, may come too close to the 115 surface, or pipes or other obstructions may be in the way. Fig. 9 illustrates one way in which I enable the post to be employed in such locations, and to be conveniently housed when desired. I provide a shallow 120 socket-member 3^a, which I embed at the point where the post should stand when in use, and at some convenient adjacent point where there is no obstacle to the planting of a socket-member sufficiently long or deep to 125 accommodate the inverted post. I plant a socket-member 3 like that of Figs. 1 to 3. The base-member 2 of the post fits the two socket-members 3 and 3^a interchangeably. A separate cover 15, which also fits said 130

socket-members interchangeably, is provided. When the post is placed in working position, with its base-member seated in the socket-member 3^a, as at the left in Fig. 9, 5 the cover 15 occupies the mouth of the socket-member 3 and closes the latter, as at the right in said figure. When it is desired to store away the post, it is removed from socket-member 3^a, cover 15 is transferred to 10 the latter, and the inverted post is housed in the socket-member 3 in the manner already explained in treating of Figs. 1 to 3. In some cases it will be possible to station the traffic-post in its upright working position 15 in the auxiliary socket-member 3 of Fig. 9.

The construction shown in Fig. 10 is adapted to be shifted about from place to place, as required. It is adapted for temporary use in a given location, or for use in 20 a location where it is not desired or possible to make an opening in the surface. In such construction, the socket-member, designated 3^b, is not sunk in a roadway or the like, but is constructed to be placed upon the surface 25 of a roadway, walk, pavement, or wherever else desired. It is sufficiently heavy to obviate overturning when the post proper is turned down by a passing vehicle.

Figs. 11 and 12 show a reversible construction employing a weight, in lieu of a spring, 30 for actuating the post-member. In these figures, the post-member is designated 1^c, the base-member 2^c, and the socket-member 3^c. The post-member has a convex lower end 35 which fits a concave bearing in one side of the base-member 2^c when the parts are in their working position shown in Fig. 11. A chain 16, attached by one extremity thereof to the center of the said convex lower end of 40 the post-member, extends through a central hole in the base-member, and has a weight 17 attached to its other end. In Fig. 11 the weight hangs suspended by the chain from the lower end of the post-member, holding 45 the convexity of said end to the concave seat in the upturned side of the base-member 2^c. The effect of the weight is to cause the post-member to stand erect, but the post-member is permitted to swing down transversely in 50 any direction when driven against. The suspending weight operates to cause the post-member to erect itself again after having been forced over transversely. Fig. 12 shows the post-member housed within the socket- 55 member, the base-member 2^c being reversely applied to its seat at the top of the socket-member. In inverting the parts as in Fig. 12, the cylindrical body of weight 17 is allowed to pass downward within the central 60 opening of the base-member until the flange 17^a upon one end of such weight occupies the counterbore 2^x in the base-member. In Fig. 65 the top of the base-member is flush with the roadway, and the top of weight 17 is flush with that of the base-member. The

ring 17^b that is shown loosely connected with the weight 17 serves in lowering the parts into the socket piece and in lifting them out therefrom.

The general construction shown in Figs. 70 11 and 12 permits the base-member to be employed, if desired, as the cover of a man-hole of a sewer, conduit, or the like, in which case the weight in Fig. 11 and the post-member in Fig. 12 will hang suspended within 75 the manhole.

Figs. 13 and 14 show a construction in which the foot 10^d of the post-member 1^d has a circumferential projecting flange 10^e which rests upon the top edge of the base-member 80 2^d, the latter being constituted by a short hollow cylinder removably occupying the upper portion of the socket-member 3^d. The body of the foot 10^d extends down within the base-member. A downward pull is exerted upon the foot 10^d, to hold its flange 85 10^e seated upon the top edge of the sleeve-like base-member, by a contracting spiral spring 11^d having its upper end engaged with a screw-eye 13^d in connection with foot 90 10^d, and its lower end engaged with a hook in connection with the lower portion of a bail 12^d extending down from the base-member. The spring holds the post-member and 95 foot to be rocked with the foot bearing upon the top edge of the base-member, and operates with a tendency to restore the post-member and foot to their erect position as soon as they are freed from the pressure 100 which overturned them. As the post-member and foot are rocked downward the foot-member will partly slide or slip outward upon the said top edge until the shoulder 10^f of the foot-member engages with such edge, which will prevent the foot from slipping farther. As the post-member and foot 105 return to their normal erect position under the action of the spring 11^d, the shape of the foot will cause it to center itself properly within the sleeve-like base-member. 110

I contemplate in some instances equipping the post-member in the case of each of the forms shown herein with a lamp or lamps, preferably either electric or acetylene, to serve as a signal at night. Fig. 13 shows a 115 lamp 18 applied to the top of post-member 1^d, and a second lamp 18^a applied to the top of foot 10^d. The walls of the post-member are made with openings, that are closed with transparent or translucent material 1^c, such 120 openings serving as windows to permit the light to show through from within. In Figs. 13 and 14 the wires 19 leading to the lamp extend transversely through holes in the ground socket 3^d and base-member 2^d and 125 upward through a hole 19^d in the foot 10^d, such holes being bushed with insulating material 19^e. To accommodate the swinging movements of the post the wiring is made extensible by providing an excess length 130

thereof to produce slack below the foot 10^d as shown.

Post-members of traffic-posts embodying the invention may or will be provided with 5 words or signs of a character to give the desired warning, direction, or other information.

What is claimed as the invention is:—

1. A traffic post comprising a base-member 10 having a post-centering upstanding portion surrounded by a post-supporting portion, a post member fitting over the said upstanding portion, centered thereby, and resting upon said post-supporting portion, and 15 means constantly urging the post-member toward said base-member and yieldingly holding the foot of the post-member to said supporting portion, thereby normally keeping the post-member erect while permitting 20 it to tilt in different directions.
2. A traffic-post comprising in combination a post-member, a base-member on which the foot of said post-member rests, a socket-member with which the said base-member is 25 removably combined also adapted to receive the base-member and post in reversed position, and means for yieldingly maintaining said post-member normally in an erect working position relative to said base-member, 30 permitting it to yield without breakage when struck by a passing vehicle to permit a vehicle to pass over it, and automatically restoring it to the said working position when the vehicle has passed, all constructed 35 and arranged to permit the base-member and post-member to be reversed and the post-member supported or housed in the socket-member.
3. In combination, a traffic-post member, a 40 base in connection therewith, and a socket-member in which said traffic-post member may be completely housed in inverted position, said base forming a closure for the socket-member when the post-member is thus housed.
4. A traffic-post comprising, in combination, a base-member and a post-member, one

thereof having a centering boss that enters the other, said post-member having a radially-extending foot engaging with an annular supporting bearing on the other, and means for holding said post-member normally in an erect working position, permitting it to swing when struck by a passing vehicle, and automatically restoring it to 55 erect position again.

5. A traffic post comprising a ground socket-member, a base-member detachably mounted in said ground socket-member, a post movably connected to said base-member, and resilient means for maintaining said post in a normal position.

6. A traffic post comprising a ground socket-member, a base-member detachably mounted in said ground socket-member, a 60 post movably connected to said base-member, and resilient means extending between said base member and said post for maintaining said post in a normal position.

7. In a street post, a ground socket, a 70 base-member detachably mounted in said ground socket, a post, a lamp carried by said post, means for resiliently connecting said post to said base-member, and extensible supply conducting means for said lamp combined with said elements.

8. A traffic regulator comprising a fixed base plate, an upwardly extending conoidal centering member secured thereupon, a tubular semaphore post positioned over said centering member and normally standing in a vertical position upon the base plate, and a resilient connection between the post and centering member whereby the post may have yieldable radial movement in relation 85 to the centering member and upon the base plate.

In testimony whereof I affix my signature in presence of two witnesses.

PAUL HANNAGAN.
